UNITED STATES PATENT OFFICE.

OLIVER McCARTHY, OF MERIDEN, CONNECTICUT, ASSIGNOR TO THE
MERIDEN BRITANNIA COMPANY, OF SAME PLACE.

DESIGN FOR A COFFIN-SCREW.

SPECIFICATION forming part of Design No. 18,796, dated December 11, 1888.

Application filed October 22, 1888. Serial No. 288,847. Term of patent 14 years.

To all whom it may concern:

Be it known that I, OLIVER McCARTHY, of Meriden, in the county of New Haven and State of Connecticut, have invented a new

- 5 Design for a Coffin-Screw; and I do hereby declare the following, when taken in connection with accompanying drawing and the letters of reference marked thereon, to be a full, clear, and exact description of the same, and
10 which said drawing constitutes part of this specification, and represents a perspective view.

This invention relates to a design for the article used for coffin-trimming, and which
15 consists of an ornamental head upon a screw to be secured to the lid or cover of the coffin and present an ornamental or emblematical appearance; and the design consists in the head of the screw representing a kneeling
20 child with wings spread.

The head of the screw or shank *a*, as shown

in the accompanying illustration, represents a figure of a child kneeling upon a base, *b*, and as provided with wings represented as spread. 25

The particular shape or ornamentation of the base is immaterial to the invention, a base of some character, however, being usually represented in connection with the ornamental head of the screw. 30

I claim—

The herein-described design for a coffin-screw, consisting in the head of the screw, representing a kneeling child with wings spread, the child represented as kneeling upon a base, as shown in the accompanying illustration. 35

OLIVER McCARTHY.
